US00D532666S

(12) **United States Design Patent** (10) **Patent No.:** **US D532,666 S**
(45) **Date of Patent:** **** Nov. 28, 2006**

(54) **POWER TOOL**

(75) Inventor: **Wen-Yao Chi**, Taichung County (TW)

(73) Assignee: **Mobiletron Electronics Co., Ltd.**,
Taichung Hsien (TW)

(**) Term: **14 Years**

(21) Appl. No.: **29/252,090**

(22) Filed: **Jan. 19, 2006**

(51) **LOC (8) Cl.** **08-05**

(52) **U.S. Cl.** **D8/68**

(58) **Field of Classification Search** **408/125,**
408/234, 241 R, 20, 124; 451/358; 310/50;
227/8, 114, 120, 130, 136, 142; D8/14.1,
